(57) **CLAIM**

The ornamental design for a charging connector, as shown and described.

DESCRIPTION

FIG. 1 is a perspective view of a charging connector according to a first embodiment;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view of a charging connector according to a second embodiment;

FIG. 9 is a front elevation view of the charging connector of FIG. 8;

FIG. 10 is a rear elevation view of the charging connector of FIG. 8;

FIG. 11 is a left elevation view of the charging connector of FIG. 8;

FIG. 12 is a right elevation view of the charging connector of FIG. 8;

FIG. 13 is a top plan view of the charging connector of FIG. 8; and,

FIG. 14 is a bottom plan view of the charging connector of FIG. 8.

The broken lines in the drawings illustrate portions of the charging connector which form no part of the claimed design. The difference in shading in the drawings indicates a contrast of appearance and is not intended to depict any particular color or material.
